UNITED STATES PATENT OFFICE.

FRED DRAPER, OF DANVILLE, ILLINOIS.

APPAREL-COLLAR.

No. 829,063.

Specification of Letters Patent.

Patented Aug. 21, 1906.

Application filed September 14, 1905. Serial No. 278,509.

To all whom it may concern:

Be it known that I, FRED DRAPER, a citizen of the United States, residing at Danville, in the county of Vermilion and State of Illinois, have invented certain new and useful Improvements in Bi-Button Collars; and I do declare the following to be a full, clear, and exact description of the invention, such as will enable others skilled in the art to which it appertains to make and use the same.

My invention relates to improvements in collars, and more particularly to means for insuring the proper set of the collar around the neck of the wearer.

15 The object of the invention is to provide a turn-down collar with a simple, durable, inexpensive, and efficient means for holding the points of the collar in contact when it is buttoned around the neck, so that a perfect fit 20 will be insured and no discomfort or inconvenience will be caused the wearer.

25 Figure 1 is a perspective view of a turn-down collar with my improvements applied thereto, the collar being in its buttoned or closed position; and Fig. 2 is a similar view showing the collar opened or unbuttoned.

In practicing my invention I construct a collar 1 in the usual manner and with the usual lower buttonholes 2, which engage the 30 button 3 upon the neckband of the shirt and provide in the upper portion of the meeting ends or flaps 4 5 of the collar extra buttonholes 6, which are adapted to receive an additional fastening-button 7. These buttonholes 6 are preferably vertically disposed, as shown, and arranged at the upper portion of the flaps 4 5, so that the top or upper edge of the collar will be held closed to insure a perfect fit. The provision of the buttonholes 6 and 40 the use of the button 7 prevents the usual button 2 from acting as a pivot and permitting the ends of the collar to swing open or apart. This additional fastening-button 7 will also prevent the collar from mashing down or collapsing in warm weather. It 45 may also be used for attaching a necktie thereto, so that the latter may be worn high, as is desirable in some cases. If the tie is fastened to the upper button, both buttons will be concealed with certain styles of ties. The provision of the buttonholes 6 does not interfere in any way with the laundering of the collar and will last as long as the collar. 50 The flap 4 is curved, as shown at 4', to permit of its being lapped to and underneath

the flap 5, and said flap 5 is interposed between the fold of the opposite end of the collar and its neckband, so as to conceal the larger portion of the flaps when lapped together. By reversing the buttonholes the 60 upper ones of the flaps are constructed vertical for the reason that if the same were constructed crosswise the same as the lower ones it would be impossible to adjust a button therein, as the meeting ends of the collar are 65 arranged so close together that if the buttonholes were crosswise at this point they would be partially concealed by the ends of the collar and, as before stated, the button could not be placed in the buttonholes if the same 70 were made crosswise. Further, the vertical buttonholes when the stud engages the same serve to hold the upper ends of the collar together to prevent lateral slipping movement of the same, as will be readily seen. The 75 button 7 will not cause any discomfort or inconvenience to the wearer and can be very quickly applied to and removed from the collar.

From the foregoing description, taken in 80 connection with the accompanying drawings, the construction and operation of the invention will be readily understood without requiring a more extended explanation.

I wish it to be understood that my improved turn-down collar is provided with a neckband having flaps or extensions 4 and 5, constructed of different sizes and lengths, each having a pair of buttonholes arranged in line one above the other, the upper ones of 85 each pair being constructed vertical and arranged approximately near the vertical edge line on the opposite ends of the turn-down portion of the collar. The longer flap 5 is slightly curved at its upper corner, as shown 90 at 5', to permit of its being interposed between the opposite end of the collar and neckband. The shorter flap or extension 4 is provided with a curved edge 4', which extends below the central edge portion of the 100 same. The curvature 4' serves to reduce the thickness of the two flaps 4 and 5 when lapped together, whereby the neck of the wearer is prevented from being pinched between the two edges of the flaps. Said arrangement of the two flaps also relieves the 105 neck to a great extent from abrasion when the two flaps are brought together. Further, the two vertical buttonholes register one with the other and a collar-button secured in 110

said buttonholes prevents lateral movement of the two flaps at their upper portions when secured together.

Having thus described my invention, what I claim as new, and desire to secure by Letters Patent, is—

A turn-down collar comprising the neck-band constructed with flaps of different sizes and lengths, each of which is provided with a pair of buttonholes arranged in line one above the other, the upper ones being constructed vertical and arranged approximately near the vertical edge line on the opposite ends of the turn-down portion of the collar, said longer flap having a slight curve at its upper corner to permit of its being in-

terposed between the opposite end of the turn-down portion of the collar and neck-band, the smaller flap being provided with a curved edge which extends below the central edge portion of the same, said curvature serving to reduce the thickness of the two flaps when lapped together, and the vertical buttonholes serving to register one with the other, substantially as specified.

In testimony whereof I have hereunto set my hand in presence of two subscribing witnesses.

FRED DRAPER.
